(57) **CLAIM**

The ornamental design for a junction box with cable management, as shown.

DESCRIPTION

FIG. 1 is a perspective view of a junction box with cable management in accordance with the present design;

FIG. 2 is a front view of the junction box with cable management shown in FIG. 1;

FIG. 3 is a rear view of the junction box with cable management shown in FIG. 1;

FIG. 4 is a plan view of the junction box with cable management shown in FIG. 1;

FIG. 5 is a bottom view of the junction box with cable management shown in FIG. 1;

FIG. 6 is a left side view of the junction box with cable management shown in FIG. 1; and

FIG. 7 is a right side view of the junction box with cable management shown in FIG. 1.

The broken line showing of attachment aperture indicia on the attachment panel in FIG. 6 is for the purpose of illustration and forms no part of the claimed design.

1 Claim, 6 Drawing Sheets
